UNITED STATES PATENT OFFICE

2,603,010

COUNTERBALANCED IRONING PRESS AND
OPERATING MECHANISM

Edwin E. Fester, Austin, Tex.

Application July 26, 1943, Serial No. 496,189

8 Claims. (Cl. 38—36)

1

This invention relates to an ironing press of the heavy duty type for laundry and dry cleaning purposes. In my co-pending application, Serial No. 379,317, filed February 17, 1941, now Patent No. 2,476,363, dated July 19, 1949, there is disclosed a number of types of laundry presses, and the ironing press of this application constitutes an improvement thereover.

It is an object of the present invention to provide the press with a specific type of automatic thickness compensator to automatically take care of work which has different thicknesses and to compensate for the settling of the padding. A further object resides in the controls for operating the press throughout the various movements of the head and bed members. A still further object resides in the provision of locking means to latch the head member in the various positions, one including the extreme open position and another the partially closed position, and these positions representing the extreme positions of a so-called pendulum stroke of the head member. Another object of the invention relates to the type of press in which a pre-stressed spring is employed to provide the ironing force for the head member.

Further objects and aims of the invention will be apparent from the following description, when considered in connection with the accompanying drawings, in which:

Figure 1 is a side elevation, partly in section of the press in the full open position.

Fig. 2 is a similar view with the parts in the latched down position, with the head and buck spaced a slight distance from each other.

Fig. 3 is a similar view with the parts in a position to precompress the material to be pressed with the thickness compensator actuated.

Fig. 4 is a similar view with the parts in the pressing position.

Fig. 5 is a rear elevation of the press with the parts in the position of Fig. 2.

Fig. 6 is a perspective view of a frame of the press.

Fig. 7 is a perspective view of a yoke of the press.

Fig. 8 is a perspective view of a bell crank lever.

Fig. 9 is an exploded perspective view of a spring and its link.

Fig. 10 is an exploded perspective view of the thickness compensator.

Fig. 11 is an exploded perspective view of a pedal mechanism, and

Figs. 12 to 14 are perspective views of various detailed elements of the machine.

The press comprises the usual head member 1, a bed member or buck 2, a handle 3 and a yoke 4. As seen in Fig. 1, the head member 1, in the raised position, affords an ideal working clearance above and behind the buck 2, with the handle 3 within easy reach of the operator. The yoke 4 is pivoted at 6 to the upper part of a frame 5 composed of heavy sheet iron elements welded or otherwise held together to form a rigid box-like structure of angle irons with spaced base plates 101 and 102 by means of which the press may be supported or bolted to the floor or embedded in concrete.

The yoke 4 and head member 1 are positively held or locked in the press open position, Fig. 1, by means of a toggle prop stick or lever 10, 13 which is hinged at one end to the lower end 7 of the yoke 4. The prop stick consists of double lower members 10 and a single upper member 13 hinged or pivoted to each other by means of a pin 8. The other end of the prop stick is provided with a pin 9 in a bearing 9' which connects the lower links or members 10 with an arm 11. The members 10 are actually two links with the single link 13 pivoted between them at pin 8 at one end and the bearing 9' between the links 10 at the other end so that member 13 is single and members 10 double. The arm 11 is pivoted to the frame at 1 and by means of a pivot pin 12. The prop stick 10 and 13 not only serves to latch the head and yoke in the press open but also latches the head 1 in the partially closed position, Fig. 2, and these two positions constitute a so-called pendulum stroke of the yoke 4 and head member 1.

One or more springs 14, preferably two, of which one end is secured to a lug 103 on an arm 104 of the yoke 4 and the other end on a lug 105 secured to the bottom part 106 of the frame 5, are tensioned with sufficient force to throw the head member 1 rapidly upward in which position the yoke is latched, Fig. 1. As seen in Fig. 1, the head opening springs 14 are practically in line with the pivot point 6 and therefore such springs are not counter-weighting the head 1 in a manner similar to known machines. The spring 14 acts to kick the head upward from the closed position, but need not exert much force thereon in the raised position as inertia carries the head upward into latching position.

The handle 3, pivoted at 15 to the yoke 4, is suitably connected by the linkage 107, also connected to the pivot 15, to a bell crank lever 108 pivoted on the underside of the arm 104 at 108', 55 which acts, when the handle 3 is moved slightly

downward, to release the prop stick 10 and 13 so that the head member 1 falls forward and downward towards the closed position, Fig. 2. In other words the handle member 3 is a lever pivoted at the point 15 to the yoke 4 and a downward movement on the handle 3 causes the tension link 107 to pull the bell-crank 108 counter-clockwise about its pivot. The pendulum action makes it possible to utilize a comparatively heavy cast iron head to be opened and closed quickly with very little effort, but an aluminum or other metal or alloy head may be used if desired. The force necessary to actuate the head requires little more than the weight of the operator's hand and arm.

The upper member 13 of the prop stick has a finger 16 secured thereto which is adapted to latch against a roller 17 on the end of a double finger 18 secured between the members 10, Fig. 3. The double finger 18 is pivoted at 19 to the member 10. A rubber or resilient stop 20 secured between and to the members 10 causes the toggle prop stick to latch approximately on dead center so that the latch itself will have very little load, although the toggle is supporting considerable weight. The resilient stop 20 is carried on a web in the toggle member 10 and is intended to stop the other toggle member 13 just past where the latch is fully engaged. The toggle members 10 and 13 with the elbow at the point 8, break to the right, or toward the front of the machine, in Fig. 1, and break upward in Fig. 2.

A second finger 21 cooperates with the lever 108 to the handle 3, while a third finger 22 cooperates with a projection 23 secured on a release pedal 24. The fingers 21 and 22 are pivoted at 19 to and between the members 10. A tension spring urges the member 18 and the integral fingers 21 and 22 anti-clockwise about the pivot point 19 on the toggle member 10. The rounded cam end of the finger 16, which is integral with the toggle member 13, is held by the roller latch on the double finger 18, as shown more clearly in Fig. 2. The toggle members 10 and 13 are approximately a straight line, but when the latch member 18 is moved so that the roller rolls off the end of the member 16, the toggle will break upward. The function of the finger 22 in breaking the toggle is to cooperate with the projection 23 on the release pedal 24. When the head is latched down in the position shown in Fig. 2, a light touch by the operator's foot on the pedal 24 releases the latch at the toggle prop stick 10 and 13 and permits the head 1 to rapidly return to open position. Since the operator's effort in bringing the head downward is apt to vary from time to time, and also the force that the spring or springs 14 impart to the yoke 4 will be affected by friction and other changeable varying factors, it is desirable to mount the lower end of the toggle member 10, 13 to the movable arm 11 at the bearing 9, and to connect the arm 11 to a hydraulic check 25 by means of a hinged elbow 65. The arm 11 rests against a stiff compression spring 27 mounted on top of a post 28, which latter is welded to the base plate 101, of the frame. The purpose of this arrangement is to allow the head to travel slightly past its two positions shown in Figs. 1 and 2, and then settle back against the spring stop member 27, while the hydraulic check 25 permits it to settle back gently. In other words, when the head 1 is latched in the open or raised position the toggle prop stick 10 and 13 has straightened and latched and has taken the arm 11 upward with it until the extreme end of the pendulum stroke has been reached. The difference between the extreme

position and the actual position at which it comes to rest is the reserve necessary for safety, lest friction should cause the head 1 not to rise high enough to be latched before starting back down again. The member 11 returns against the stop member 27 by means of a tension spring 109, Fig. 11, secured at one end to the base plate 101 and the other end to an extension 110 on the arm 11.

Referring to Fig. 2, it will be noted that the head latches downward or near the closed position in a definite position each time. The padded buck 2 on which the material to be ironed has been placed is moved upward when the operator presses down on a pedal 29, causing a toggle 31 and 80 pivoted together at 30 to straighten. Since the upper member 31 of this buck lifting toggle 31 and 80 consists of a compression spring 31', the buck 2 will be moved upward more firmly against a thick garment than is the case if a thin garment is on the buck, since the latter is lifted by means of the resilient toggle. The buck 2 is secured on a supporting neck or post 38 which latter is pivoted on a pin 37 on a guide member 39 pivoted at 6 to the frame 5 on the pin as the yoke 4, as shown in Fig. 1. The pedal 29 is mounted on a rod at 77 on the end of a lever arm 78 which latter is secured on a hub 79 to which the toggle element 80 is also secured as shown in Fig. 11.

A wedge member 32 actuated by a tension spring 33 follows through the space between a stationary friction lining member 34 and a movable friction block 35 mounted on a shoe 36 which latter is pivoted on a pin 37 to a buck supporting neck 38 and a buck supporting arm or guide member 39, the latter arm being pivoted on the pin 6. The member 34 is mounted on a cross beam 67 which is welded into the frame 5. The spring 33 is connected to a bell crank lever 89 pivoted at 90 to the frame 5, and as shown in Figs. 1 to 4 a short link 89' connects the lever 89 with the wedge member 32. This tapered wedge 32, which moves into place between the two friction members 34 and 35 as the buck 2 moves upward, keeps the buck from moving back downward as the ironing pressure is applied. Fig. 3 shows the pressure pedal 29 almost down, in which position the buck 2 is raised firmly against whatever material is placed between the head and buck and the wedge 32 has slipped into place holding the pre-compression that was caused by the spring 31'. When the pedal 29 is moved furtherdownward, a lock nut 40 on the lower end of a tension link 41 is engaged by a flange 42 on a lever arm 78 to which the link 41 is also connected, causing a latch finger 43 to be moved about a pivot point or pin by means of which it is mounted to the frame. The wedge 32 is restored to its original position when the head moves upward, causing a cam 84 to push a roller 85 and a bell-crank 86 about a pivot 87, which pushes a link 88, causing a bell-crank 89 to pivot about a point 90, against the tension spring 33 and pull the wedge 32 to the right by means of the connecting link. This is shown more clearly in Figs. 1 to 4. The weight of the latch finger 43 is sufficient to cause it to return to the latched position shown in Figs. 1 to 3 when the pedal 29 is restored to its raised position. When the toggle 80 and 31 is broken, the yoke 4 and head member 1 move upwardly during which movement the cam 84, Fig. 4, rotates counter-clockwise to strike the roller 85, Fig. 1, and by the said parts 86, 88 and 89 the wedge member 32 is moved to the right, that is restored to its original posi-

tion. This takes place against the force of spring 33.

The member 11 returns against the stop member 27 by means of a tension spring 109, Fig. 11, secured at one end to the base plate 101 and the other end to an extension on the arm 11. As shown in Fig. 4 when the latch finger 43 connected to the link 41 by an intermediate link 43', Figs 1 to 4, is lifted from a hub 50, Fig. 3, a U-shaped pivot member 46 and a diamond-shaped leaf compression spring 47 are moved from the position shown in Fig. 3 to the position shown in Fig. 4, due to the kick imparted by a compression spring 48 through a rod 111, links 71 and 73 and projection 75. The U-shaped pivot member 46 is actually pivoted on the frame 5 in the lugs 54, Fig. 6, and the spring 47 is pre-stressed into position between the hubs 51 and 50, Fig. 9. The latch finger 43 contacts hub 50 in Figs. 1 to 3, but when actuated by the pedal 29 the latch finger is moved upwardly, Fig. 3 to Fig. 4, to thus free the U-shaped member 46. The pre-loaded leaf spring 47 is hinged to the pivot member 46 by means of suitable bearings 49 and slotted shaft 59, Fig. 9. The compression spring 48 bears on its upper end on the frame 5 as shown in Fig. 4 and the other end against the link or rod 48'. The lower end of this diamond-shaped leaf spring fits into a slotted shaft 51 which pivots by means of bearings 52 in the lower end of the yoke member 4. The lower ends of the tension U-member 46 pivot on pins 53 in upright arms or lugs 54, which are welded to a cross support 55, Fig. 6, of the frame 5. The pressure between the head and buck is determined by the amount of pre-loaded energy that is stored into the spring 47, when the press is assembled and it is not dissipated while it is applying pressure, Fig. 4. Since the pivot member 46 and the spring 47 practically float around the pivot points 53 and 51, it is desirable to latch the member 46 in its pressure applied position by means of a latch finger 56 and a roller 57. The roller 57 is mounted on the frame as shown in Fig. 4 by means of a shoulder screw. The latch 56 is held in place in relation to the pedal 24 by means of a tension link 112 backed by a compression spring 113 which presses against a lug 114 on a hub 79. The first part of the release pedal stroke pulls this latch member 56 off the roller 57 and the continued movement of the release pedal 24 causes the pivot member 46 to return to its pressure-off position due to engagement of link 73 and an arm 75 on member 46 shown in Fig. 3, at which time the latch finger 43 will engage the roller 45 to hold it against the kick spring 48. The last part of the stroke of the release pedal 24 also unlatches the prop stick toggle and the head is allowed to open. In actual operation the trip pedal 29 is very easy to operate and has a very short stroke. Its ease of operation is aided by means of a counterweight tension spring 58, which counterweights the buck 2 through a lever 59 pivoted on the frame at a point 60 and lifts upward by means of the roller 61, which contacts against a projection 62 on the buck guide member 39.

Referring to Fig. 3, the points of coincidence, that is the relation of the pivot point 51 at the lower end of the movable yoke 4 to the stationary point or pivot 53 on which the pivot member 46 hinges is always constant just prior to releasing the latch 43, which permits the pre-loaded spring 47 to transmit its pressure between the head and buck. When the pressure is applied the toggle prop stick 10, 13 changes from a com-

pression force to a tension force, thereby lifting the hinged member 11 away from the stop 27, as shown in Fig. 11. Since this stroke of the member 11 is considerably greater during this pressure stroke than at the time the head latches up or down, the hinged elbow 65 is provided so that the piston of the hydraulic check 25 will not have to go through this extra long travel, but will only lift about $\frac{1}{2}$ ", this lift being caused by a compression spring 63. As the release pedal 24 is forced downward and the lower end of the yoke 4 falls downward as the pressure is removed, the arm 11 lowers against the spring stop 27 without any resistance due to the hydraulic check 25, except at the extreme lower end of this stroke. That is, when a stop member 64, Fig. 11, on the arm 65 abuts against the arm 11, the short travel of the lower end of the yoke 4 at the time the pressure is applied is caused by the flexing of the yoke and frame members and the settling of the spring pad and the materials being ironed. Approximately all of this energy is restored to the reservoir spring 47 as the pressure is removed. The upper end of the leaf spring 47, that is, the pivot point between the spring and the U-member 46, exactly coincides with the main pivot point 6 between the yoke 4 and the frame.

Referring to Figs. 4 and 5, it will be noted that the buck guide arm 39 pivots on the reduced ends of the pivot pins 6. The buck support neck 38 is pinned to this guide member 39 by means of the pin 37, which pin also carries the shoe 36, but in order to force the buck to remain upright when the head is in its raised position, it is necessary to provide additional means, which is the purpose of an arm 65' at the lower end of the buck support 38. This arm 65' is provided with a roller 66, which rolls against a cross beam 67 which is welded to the frame and which supports the friction block 34. A tension spring 68 attached to the arm 65' and the frame at the point 69 maintains the roller 66 in contact with the beam 67, as the buck moves up and down. When the pressure is applied, this roller lifts away from the beam 67 and stretches the spring 68 due to the forward motion of the head about the pivot point 6.

Referring to the pedals, the release pedal 24 pivots on a shaft 70 and is on the right hand side of the machine. The adjustable trigger release finger 23 is on the double arm rear projection of this same release pedal. A second double lever 71 is hinged to the release pedal at the point 72 at one end and to a connecting link 73 at its other end at the point or pin 74. The connecting link 73 connects the link 71 to a projection 75 on the pivot member 46. The finger latch 56 is also pinned to the link 71 at a point 76. This hinged link 71 of the release pedal 24 is necessary as it is desirable to be able to open the head by pressing the pedal 24 without having applied pressure, at which time the pedal and projection 23 must release the toggle prop stick latch without moving the pivot member 46. The pedal 24 may force lever 71 and connected members 73 and 46 upwardly if the latter are in pressure applying position, but if the latter are not in pressure applying position, link 71 connected thereto may swing up out of the way, so that abutment 23 on the pedal 24 may still function. The pressure pedal system consists of the pedal 29 pivoted at a point 77 on a projection 78 which is connected to a hub 79. A long arm 80 of the buck lifting toggle is also connected to this same hub 79. The hub of the release pedal 24 is also provided with a short arm 81, on the end of

which is a roller 82, which cooperates with a flat surface 83 of the pressure pedal 29. Through the first part of the stroke of the pedal 29, the flat surface 83 reacts against the roller 82, which is stationary until pressure is applied, and causes the hub 78 to move clockwise about the shaft 10 and straighten the toggle members 80 and 31 to lift the buck against the materials to be ironed. The bracket 42 is a part of the arm 78, and this bracket 42 will actuate the release latch 43 when the pedal 29 is moved through the last part of its stroke. As the pressure is applied, the roller 82 lifts away from the flat surface of the release pedal 29, as shown in Fig. 4.

Referring to Fig. 1, a cam 84 on the right-hand side of the yoke is in contact with a roller 85. This roller is on a forked link 86, which is pivoted at a point 87 on the frame. To the lower end of the forked member 86 is hinged a curved push link 88. The other end of the link 88 is connected to an upright finger 89 on a counter-shaft 90. When the head opens the cam 84 causes the member 86 and the push link 88 to force the wedge forward against the tension spring 33, and the counterweighted buck settles downward as the wedge is withdrawn. As the head is lowered the cam 84 moves away from the roller 85, because the friction shoe 35 keeps the wedge from following back against the weight of the buck until the weight of the buck has been lifted by means of the pedal 29. In other words, the wedge is withdrawn each time the head goes up and follows back into place only when the weight of the buck has been removed, at which time it follows into place because of the tension spring 33. The counter-weight spring 58 counter-weights all except about 10 or 20 pounds in order that it will settle down each time with sufficient weight to hold the wedge, but with not too much weight which would make the wedge hard to withdraw and would cause it to chatter.

It is believed that the operation of the ironing press will be obvious from the foregoing when considered in connection with the drawings. In the full open position of Fig. 1 the article to be pressed is arranged on the buck 2 after which the operator grasps and pulls on the handle 3 to bring the head member 1 down to the position of Fig. 2. Thus when the handle 3 is moved slightly downward about the pivot 15 the latch in the prop stick 13 is released and the head moves forward and downward to the position of Fig. 2. When the head is thus latched down a light touch on the pedal 24 releases the latch at the toggle prop stick 10, 13 to return the head back up to its open position, if desired for any reason.

In the position of Fig. 2 the operator next presses down on the pedal 29 causing the toggle 31 and 80 to straighten the latter and move the padded buck 2 upward firmly against the head 1. The wedge member 32 actuated by the spring 33 will move to the left between the blocks 34 and 35 maintaining the buck in place dependent upon the thickness of the article to be ironed. The parts are now in the position of Fig. 3 in which the pressure pedal 29 is almost down and the buck 2 is raised firmly against the article to be pressed. When the pedal 29 is now moved further downward the pivot member 46 and compressed spring 47 will be moved down to the position shown in Fig. 4 to thus apply the force of the spring 47 between the head and buck and press the article between them. To release the head member it is merely necessary to press on the release pedal 24.

I claim as my invention:

1. An ironing press comprising relatively movable head and bed members, means including a collapsible toggle-prop connected to the head member for locking the head member in its extreme open position and for locking the head member in a partially closed position, the movement of the head member between the open and partially closed positions taking place in the collapsed position of the toggle-prop and representing a stroke of the head member, means adjacent the said toggle-prop for unlocking the head member, and spring means associated with the head and bed members for applying a force on the head member when in contact with the bed member as an ironing pressure between the head and bed members to press an article therebetween.

2. An ironing press comprising a frame, relatively movable head and bed members mounted on said frame, means including a collapsible toggle-prop connected to the head member for locking the head member in its extreme open position and for locking the head member in a partially closed position, the movement of the head member between the open and partially closed positions taking place in the collapsed position of the toggle-prop and representing a stroke of the head member, means adjacent the said toggle-prop for unlocking the head member, and means including a movably mounted prestressed leaf spring and means for moving the spring into a position so that the force thereof will be applied on the head member against the bed member to thereby apply an ironing pressure between the head and bed members by means of said spring when the latter are in contact with each other to press an article therebetween, said spring being connected at one end to the head member and the other end to the frame of the press.

3. A force applying machine comprising a frame, a bed member mounted on the frame, a head member mounted on the frame and pivoted to open and partially closed positions relative to the bed member, means including a collapsible toggle-prop connected to the head member for latching the head member in the partially closed position, means mounted in the frame for raising the bed member in contact with the head member to completely close the head and bed members, means associated with the mounting means for the bed member for locking the bed member in the position of contact with the head member, means mounted in the frame for unlocking the toggle-prop after the head and bed members are completely closed, and spring means for applying a force on the head member as a pressure force between the head and bed members when in contact with each other.

4. A force applying machine comprising a frame, a bed member mounted on the frame, a head member mounted on the frame and pivoted to open and partially closed positions relative to the bed member, means connected to the head member for latching the head member in the partially closed position, means mounted in the frame for raising the bed member in contact with the head member to completely close the head and bed members, means associated with the mounting means for the bed member for locking the bed member in the position of contact with the head member, means mounted in the frame for unlocking the latching means after the head and bed members are completely

closed, and spring means for applying a force on the head member as a pressure force between the head and bed members when in contact with each other, said locking means including a wedge between the bed member and the frame of the machine which is spring urged to follow-up the rising movement of the bed member until the latter is in contact with the head member.

5. A force applying machine according to claim 4, in which a pair of members are provided on the raising means of the bed member to frictionally hold the wedge member in the raised position of the bed member.

6. A force applying machine comprising a frame, a bed member mounted in the frame, a head member mounted in the frame and pivoted to open and partially closed positions relative to the bed member, means connected to the head member for latching the head member in the partially closed position, means connected to the bed member for raising the bed member in contact with the head member to completely close the head and bed members, means associated with the raising means for locking the bed member in the position of contact with the head member, means mounted in the frame for unlocking the latching means after the head and bed members are completely closed, and spring means for applying a force on the head member as a pressure force between the head and bed members when in contact with each other, said latching means including a pair of levers pivoted to each other to form a toggle prop stick when the pivots are in a substantially straight line.

7. An ironing press according to claim 6, in 35

which means are provided to move the bed member vertically into contact with the head member into its closed position to compensate for different thickness in the material to be pressed.

5. An ironing press according to claim 6, in which latch release means are provided connected to the head member and operable therefrom to release the locking means for the extreme open position upon urging the head member toward the closing position.
